HAIR WAVING APPARATUS

Peter Santurello, Columbus, Ohio

Application January 29, 1934, Serial No. 708,903

14 Claims. (Cl. 132—36)

My invention relates to hair-waving apparatus. It has to do, more particularly, with apparatus for producing that type of wave in the hair which is commonly known in the art 5 as a "Croquinole" wave which is formed by winding the hair spirally around a mandrel.

There have been several hair waving devices made and used in the past for producing waves of the type indicated which are formed by winding a strand of hair spirally around a mandrel in overlapping layers. However, all of such devices have possessed certain undesirable features. In the first place, there has been no 10 adequate means provided in such prior art devices for preventing steam or condensed moisture, formed during the waving process, from reaching the scalp of the person upon whom the process is being performed. In the past, the devices which have been used for this purpose have embodied a protector clamp having a slot extending the entire length thereof and through which the strand of hair passes. The steam or condensed moisture has a tendency to flow down through this crack onto the scalp 15 of the patron and cause discomfort to the patron or even burning of the scalp.

Another disadvantage of prior art devices is due to the fact that most of such devices are complicated in structure and are difficult to apply to the hair. In all of these devices, it has been necessary to separate a rectangular strand of hair on the head and, consequently, grip a comparatively long rectangular strand between the clamping jaws of the clamp. It has been 20 found that due to this, it has been difficult to produce a wave in the hair close to the scalp, inasmuch as some of the strands of hair of the rectangular group will be gripped at points comparatively far from the scalp. Another 25 disadvantage of prior art devices is due to the fact that such devices have usually included complicated gripping and locking devices difficult to operate and having a tendency to come unlocked. The heating units employed with these 30 prior art devices have also usually been complicated in structure. Other disadvantages have also been prevalent in prior art devices.

One of the objects of my invention is to provide hair waving apparatus of the type indicated which is very simple in structure and operation and which can be easily applied to the hair in an effective manner so that a suitable 35 wave may be produced.

Another object of my invention is to provide 40 apparatus of the type indicated embodying very

effective means for preventing steam or condensed moisture from reaching the scalp of the patron which would cause injury or discomfort.

Another object of my invention is to provide apparatus of the type indicated embodying a locking means which is of such a type that the wave may be produced in the hair even at points comparatively close to the scalp. 5

Another object of my invention is to provide apparatus of the type indicated which is provided with hair gripping means of such a type that it may be easily applied to the hair and can be easily operated to grip the hair, said gripping means being provided with locking means which will maintain the gripping action 10 on the hair. 15

Another object of my invention is to provide apparatus of the type indicated embodying a mandrel on which the hair may be wound and having means for tensioning the hair on the 20 mandrel without discomfort to the patron.

Another object of my invention is to provide a novel heating unit of very simple construction which can be used with my hair waving device 25 and which will effectively cooperate therewith.

Other objects and advantages will be apparent from the following description.

In its preferred form, my invention contemplates the provision of a protector member which is adapted to be disposed closely adjacent the scalp and which is provided with a novel type of gripping means for gripping a strand of hair close to the scalp. This protector means has a trough formed therein adapted to catch steam or condensed moisture formed 30 during the waving process. A mandrel on which the hair is wound is adapted to be disposed above the protecting means and is provided with portions at each end which aid in precluding escape 35 of moisture or steam from said trough. The mandrel is of such a type and so mounted on said protecting means that after the hair is wound thereon it may be tensioned so that a satisfactory wave will be produced. A heater 40 of special type is adapted to be slipped over the mandrel and this heater is of such a type that it will cooperate with the protecting member 45 in preventing escape of steam or moisture.

The preferred embodiment of my invention is shown in the accompanying drawings wherein 50 similar characters of reference designate corresponding parts and wherein:

Figure 1 is a perspective view, with parts broken away, showing my hair waving apparatus with my novel heater applied thereto.

Figure 2 is a plan view of my hair waving apparatus.

Figure 3 is a longitudinal section taken through the middle of the mandrel substantially 5 along line 3—3 of Figure 2.

Figure 4 is a longitudinal section taken through the protecting means substantially along line 4—4 of Figure 2.

Figure 5 is a transverse section taken substantially 10 along line 5—5 of Figure 3 and illustrating how the portions of the heating unit cooperate with the trough member of the protecting means in preventing escape of moisture or steam.

Figure 6 is a detail in perspective partly 15 broken away and illustrating how the mandrel may be mounted on the protecting means in such a way that adjustments may be made to permit rotation of the mandrel or to preclude rotation thereof in either direction.

Figure 7 is a detail partly in section illustrating 20 how the mandrel may be mounted on the protecting means in such a manner that it may be completely removed therefrom when desired.

Figure 8 is a perspective view illustrating the 25 device on which the hair is to be wound, the pad which is placed around the hair on the mandrel and my novel heater arranged in spaced disassembled relation.

Figure 9 is a view illustrating how the hair 30 may be wound on the mandrel of the device shown in preceding figures.

Figure 10 is a view illustrating how the gripping means for gripping the strand of hair close to the scalp may be operated.

Figure 11 is a view illustrating how the mandrel 35 may be turned to tension the hair after it is wound thereon.

Figure 12 is a view illustrating the device after 40 the hair has been wound and tensioned on the mandrel and showing how the pad which is saturated with waving fluid may be placed around the hair on the mandrel.

Figure 13 is a view showing the device after 45 the pad has been wound around the mandrel.

Figure 14 is a perspective view showing my 50 hair waving device after the hair has been wound thereon with my novel heating unit applied thereto.

Figure 15 is a transverse section taken substantially 55 on line 15—15 of Figure 14.

Figure 16 is a side elevation of a slightly modified form of my device, the mandrel which will be mounted therein not being shown.

Figure 17 is a transverse section taken substantially 55 on line 17—17 of Figure 16.

Figure 18 is a longitudinal section of a portion of my device showing the mandrel thereof disposed within the housing provided therefor.

Figure 19 is a detail, partly in section, of the 60 right hand end of the device illustrated in Figure 18.

Figure 20 is a detail showing how the mandrel 65 may be extended from one end of the housing and showing how the stop member prevents complete removal of the mandrel from the housing.

Figure 21 is a perspective view, partly broken away, showing the mandrel in position in the 70 housing with the hair wound thereon and showing the gripping means on the protecting means gripping the strand of hair and also illustrating diagrammatically how the heater is applied to the device.

Figure 22 is a perspective view illustrating how 75

the protecting means and the heating unit may be combined into a single unit.

With reference to the drawings, and particularly to the Figures 1 to 5, inclusive, my invention is shown as preferably comprising a protecting member 1 which will be the portion of my apparatus closest to the scalp. This protecting member 1 is preferably made of some suitable material such as bakelite or wood which will not readily conduct heat. As previously stated, it is important that this member be of such a type as to prevent steam or condensed moisture, produced during the waving process, from reaching the scalp. The member 1 is comparatively long and is preferably slightly longer than the mandrel 2 which is mounted thereon in a suitable manner which will be later described in detail.

The member 1 is preferably substantially solid but has a removable portion 3 suitably fastened 20 thereon which permits the placing of the operating mechanism for the hair gripping means in a chamber 4 formed in the lower surface of the member 1. The member 1 has a longitudinally extending trough 5 formed in its upper surface and adapted to extend substantially the entire length thereof. As will be explained later, this trough is adapted to catch steam or moisture and retain it therein in order to prevent it from reaching the scalp.

The hair gripping means for gripping the hair close to the scalp will now be described in detail. This gripping means is of such a type that the strand of hair may be slipped therein at a point close to the scalp even after the free end of the strand is wound on the mandrel. It is also of such a type that the hair may be blocked off into substantially square bunches to form substantially square strands or bunches, as distinguished from rectangular 40 bunches formed when using prior art devices to produce waves of the spiral type, and then gripped by the gripping means close to the scalp.

It will be apparent from Figures 1, 2 and 4 45 that an open ended slot 6 is formed in one side of the member 1 into which a strand of hair may be slipped. This slot extends into the side edge of the member 1 but its innermost point 7 is spaced a considerable distance from the center of the trough 5 formed in the member 1. Thus, at the point 7, there will be a lip 8 which will prevent fluid from running from the trough 5 at this point. The walls of this slot 6 are curved suitably in all directions outwardly as indicated at 9 in order to eliminate any sharp edges which might injure the hair.

Within the chamber 4, plate 10 is mounted and is adapted to slide back and forth therein. This plate is flat and has an open ended slot 60 11 formed in its outer end. This slot 11 is arranged at right angles to the slot 6. On the outer end of plate 10, two fingers 12 and 13 are produced by formation of the slot. The finger 12 is much longer than the finger 13, the latter being outermost and close to the outer edge of the protecting member 1. The finger 12 is adapted to project over into the portion of the chamber 4 (Figure 4) which is at the right hand side of the slot 6 even when the plate 10 is adjusted over to the left as far as possible. Also, when this plate is adjusted into such position, the finger 13 will not project out into the slot 6. Thus, the strand of hair may be readily slipped therein.

The means for operating the gripping means comprises a shaft 14 which is rotatably mounted in the member 1 above the plate 10. This shaft has a knurled knob or nut 15 on its outer end by which it may be turned. The shaft 14 is also provided with a helical thread or worm 16, which meshes with slots 17 formed on the plate 10. By rotating the shaft 14 in either direction, the plate 10 may be moved longitudinally. As previously stated, when in the position illustrated in Figure 4, the strand of hair may be slipped into the slot 6. Then, if the shaft 14 is rotated to move the plate 10 to the right as far as possible, the strand of hair will be gripped firmly between the inner end of slot 11 and the right hand side of slot 6. Furthermore, because of the worm and gear structure, the plate 10 will be locked in any position to which it is adjusted.

The end of the protecting member 1 opposite to that where the knob 15 is disposed is provided with an upwardly extending bifurcated lug 18 integrally formed thereon. If this member 1 is made of wood or bakelite, it preferably has a metal bushing 19 inserted in the bifurcation of the lug. This bifurcated lug is adapted to receive an outwardly extending stub shaft 20 of substantially square cross-section disposed on one end of the mandrel 2. The stub shaft 20 and the lug 18 have corresponding holes through which a pin 21 may be extended in order that the mandrel 2 will be pivotally or hingedly mounted on the member 1.

The mandrel 2 is preferably of the shape shown, being of small cross-section at its middle portion and gradually increasing in cross-section towards its ends. It preferably has a knob or enlarged portion 22 formed on one end and a similar portion 23 on the other end. These portions 22 and 23 have the same curvature as the inner surface of the trough 5 in order to prevent leakage of fluid from the trough past these members when the mandrel is positioned over the trough. The upwardly extending lug 18 at the right hand end of the member 1 will, however, prevent escape of fluid from the trough at such end.

The shaft 20 at the end of the mandrel has a cylindrical portion 24 formed on its inner end which is disposed in a socket 25 of cylindrical form produced in the end of the mandrel 2. This socket 25 is of slightly greater diameter than the portion 24 and is adapted to receive a coil spring 26 which is disposed therein in surrounding relation to the portion 24. One end of the spring 26 extends into an opening 27 formed in portion 24 but the other end of the spring is free. This spring serves as a clutch to permit rotation of the mandrel 2 in one direction, but to preclude rotation thereof in an opposite direction. Thus, as viewed from the left hand end of the mandrel in Figure 3, the mandrel will be permitted to rotate in a counter-clockwise direction but rotation in a clockwise direction will be precluded. A removable cap 28 is fastened on the right hand end of mandrel 2 in order to keep the enlarged portion 24 in the socket 25.

In order to secure the free end of the strand of hair to the mandrel, I provide a member 29 which extends longitudinally of the mandrel and which is swingable between operative and inoperative positions. This member 29 has prongs 30 formed on one end which fit into radial slots formed in the member 22. Pivot 31

extends into member 22 and through suitable openings in the prongs 30. Thus, the member 29 is pivotally mounted on the mandrel so that it may swing between inoperative position and operative position. This member 29 is of such a shape that it will extend part way around the mandrel when in its operative position, shown best in Figures 2 and 4. When in operative position, it embraces the mandrel and will grip a strand of hair if the free end is disposed between this member and the mandrel and the hair is then wound around this member and the mandrel. In order to maintain normally the member 29 in its operative position, I provide a spring 32 at the end of the mandrel where the member 29 is pivoted, which will exert a slight downward pressure in order to keep the member 29 in embracing relation to the mandrel. However, when desired, the resistance of this spring 32 may be overcome and the member 29 may be swung upwardly. The member 29 is further provided with a series of spaced openings 33 which will permit the waving fluid to reach the hair disposed therebeneath.

As previously stated, the mandrel 2 may be rotated only in a counter-clockwise direction relative to the portion 24 which extends into the socket 25 formed in the end of the mandrel. I preferably provide means which may be readily gripped by the fingers for rotating the mandrel 30 in the said direction. This means comprises a key member 34 which is disposed at the end of the mandrel opposite to where it is pivotally connected to the member 1. This key member 34 embodies a pin 35 extending into a socket 36 formed in the end of the mandrel. This pin has a slot 37 formed therein and extending longitudinally thereof a substantial distance. A pin 38 extends through this slot 37 and permits reciprocation of the pin 35 in its socket, but prevents the complete removal thereof. Also, it prevents rotation of pin 35 in the socket 36. The outer end of the pin has a transversely extending member 39 on its outer end which may be gripped in order to turn the mandrel. When the key is disposed in the mandrel, this member 39 will be disposed in a slot 40 formed in the outer end thereof. This member 39 projects slightly from the ends of slot 40, as indicated at 41, in order that the key may be readily withdrawn from the mandrel. It will be apparent that when the key 34 is not in use, it will be disposed wholly within the mandrel. However, when the key is to be used for rotating the mandrel, it may be withdrawn 45 readily and firmly gripped, as indicated by the dotted lines in Figure 1. When the key is withdrawn as far as possible, it will project out from the end of the mandrel a sufficient distance past the knob 15 so that the mandrel may be 50 rotated without the knob 15 interfering with the fingers.

When using this device, it is preferable to separate the hair into a small substantially square bunch or strand. Because of the particular gripping means which I have provided, it is possible to grip such a strand close to the scalp and, consequently, the wave will be formed even at the innermost portions of the hair. The free end of the strand of hair is then placed 55 beneath the gripping member 29, as illustrated in Figure 9, and then the hair is wound around the mandrel and also over the member 29 in a counter-clockwise direction. In producing a wave of the type indicated, which this device is 60

particularly applicable to produce, the hair is wound around the mandrel 2 spirally and in overlapping layers. As the hair is wound on the mandrel, the mandrel moves closer to the scalp and, during this winding operation, the strand of hair is spread in the usual manner.

When a point closely adjacent the scalp is reached, the member 1 is swung up into position below the mandrel, as indicated in Figure 10, and the strand of hair is brought closer together and slipped into the gripping means. The gripping means is of such a type that even after the free end of the strand of hair is secured to the mandrel and the hair is wound thereon, the portion of the strand close to the scalp may be slipped bodily thereinto. The gripping means is then operated by gripping the knob 15 with the fingers and causing movement of the plate 10 in order to grip firmly the strand of hair. As previously stated, this gripping device is self-locking so that there will be no danger of the gripping means releasing its grip on the strand of hair.

In order to tension the hair on the mandrel so that it will be properly waved, the key 34 is pulled out of the mandrel and the mandrel is then rotated in a counter-clockwise direction indicated by the arrow in Figure 11 to cause tightening of the hair on the mandrel. Since the strand of hair will be gripped close to the scalp by the gripping means, there will be no danger of causing discomfort to the patron during tightening of the hair on the mandrel. Tightening of the hair on the mandrel also causes the mandrel to be held down firmly in position on the member 1. The knobs 22 and 23 on the ends of the mandrel will be seated firmly in the trough 5 of member 1 so that there will be no danger of fluid running from the trough past these members. Thus, the mandrel will be held firmly in position on the member 1 merely by the pull of the hair.

After the hair is tensioned on the mandrel as described, a pad 42 (Figures 8 and 12) is placed around the mandrel. This pad 42 is of some suitable material and is adapted to be saturated with a waving fluid. One edge of this pad is provided with an open ended slot. This edge of the pad is stiffened by small strips 44 of metal or other suitable material. In placing the pad on the mandrel, the edge with the stiffening members therein is placed underneath the mandrel and above the member 1, as shown in Figure 12. The slot 43 will extend around that portion of the hair passing downwardly from the mandrel through the gripping means, as shown in this figure. The pad may be wrapped around the mandrel, as shown in Figure 13, so that substantially all of the hair on the mandrel will be covered. The next step in the waving process will be to apply a heating unit 45 to my device.

This heating unit 45 is of novel and extremely simple construction. As shown in Figure 15, it merely embodies an outer casing 46 and an inner casing 47 spaced apart and having a heating element 48 disposed in the space formed between these casings. As previously stated, the knobs 22 and 23 on opposite ends of the mandrel are of the same diameter. The inner casing 47 forms almost a complete circle, as shown in Figure 15, and is only slightly greater in diameter than the knobs 22 and 23. The lowermost edges of the casing 47 ter-

minate a substantial distance below the center of the casing 47 and the knobs 22 and 23, as indicated at 49.

In applying this heater to the mandrel, one end is slipped over the knob 22 and the heater is then moved longitudinally until properly positioned on the mandrel. Since the edges 49 terminate at the position indicated, it is necessary to slip the heater on in this manner. When the heater is properly positioned on the mandrel, one end thereof will be closed by the knob 23 and the other end by the knob 22. As shown in Figure 14, these knobs will completely fill up the space at the ends of the heater. Thus, the knobs 22 and 23 not only serve the purpose of preventing the fluid from running from the ends of the trough 5 formed in member 1 but they also prevent escape of heat from the ends of the heater. As shown in Figure 15, the edges 49 of the inner casing 47 extend down in overlapping relation to the upper edges of the trough. Thus, escape of heat and steam at these points will be precluded. Due to the cooperation of the heater, mandrel and the member 1, the heater unit, as well as the other members, may be made extremely simple and serve their purposes very effectively.

In some instances, it may be desirable to have the mandrel mounted on member 1 in such a manner that the mandrel might be rotated in both directions. Thus, in Figure 6, I show a mandrel 50 of practically identical construction with the mandrel 2. The yoke 51, which will project up from the end of a member identical with member 1, has a block 52 pivotally mounted therein. The end of the mandrel has a shaft or extension 53 extending through an opening formed in this block 52. The extension 53 is slideable longitudinally of the block. When in the position illustrated, the end of the extension 53 projects from the block as shown. This end has an annular groove 54 formed therein. A longitudinally extending slot 55 is formed in the periphery of the extension 53 and the outer end of this slot communicates with the groove 54. The upper side of the block 52 has a pin 56 disposed therein which is adjustable up and down and which is normally held down by a spring 57. This pin normally extends down into the slot 55. The mandrel 50 will be provided with a spring clutch of the type previously described for permitting rotation of mandrel 50 relative to the extension 53 in one direction but precluding relative rotation in the opposite direction.

It will be apparent that with the parts in the position indicated in Figure 6, the mandrel 50 may be rotated in one direction relative to the extension 53 in order to tighten the hair but will be precluded from rotating in the opposite direction. Bodily rotation of extension 53 in block 52 will be precluded because pin 56 extends into slot 55. However, if the extension 53 is moved longitudinally in block 52 in the direction of the arrow until the pin 56 projects down into the annular groove 54, the mandrel 50 together with extension 53 may be rotated in either direction since bodily rotation of the extension in the block in either direction will be permitted. This is desirable as it facilitates removal of the hair from the mandrel.

In Figure 7, I have shown a slightly different structure. In this figure, a block 52' is shown

which is similar to block 52 of Figure 6 and which is mounted on a member similar to member 1 in the same manner. However, the mandrel 50 in this instance has a square extension 58 on its end. This extension projects into a square opening formed in the block 52'. When in position in the block, the extension projects slightly outwardly therefrom and has a groove 59 formed therein. A spring 60 serves as a latch member by projecting down into the groove 59 for keeping the extension 58 in position in block 52'. It will be apparent that block 52' is pivotally mounted and, consequently, mandrel 50 may be swung up and down. Also, the mandrel 50 may be completely removed from the member corresponding to member 1 by raising the spring 60 to the position indicated by the dotted lines. In this position, withdrawal of extension 58 from block 52' will be permitted if the mandrel 50 is moved longitudinally in the direction indicated by the arrow. It will be understood that the mandrel 50 will be provided with a spring clutch as before which will permit rotation of mandrel 50 relative to extension 58 in one direction but will preclude relative rotation in an opposite direction when the extension 58 is in position in the block 52'. Thus, with this structure, the mandrel may be completely removed from the protecting member.

Although I usually prefer to wind the hair on the mandrel first and then grip it near the scalp by applying the protecting member thereto, if the mandrel is made removable from the protecting member, I may first apply the protecting member and grip the hair close to the scalp, and then wind the hair on the mandrel and mount the mandrel on the protecting member. Figures 16 to 21, inclusive, illustrate a modified form of my hair waving apparatus. In this form, the member 1 and the gripping mechanism for gripping the hair adjacent the scalp are practically identical with that previously described. Also, the member 1 has a trough 5 formed in its upper surface, as before. However, in this trough is disposed the lower portion of a housing 61. This housing 61 is of circular cross-section and has substantially the same radius of curvature as that of the bottom of the trough 5. Thus, the housing 61 will fit nicely in the trough and can be held therein permanently in any suitable manner.

The housing 61 may be made of metal or other suitable material and is of cylindrical form, having its left hand end (Figure 18) open and its right hand end closed, as indicated at 62. This housing 61 is adapted to receive a mandrel 63 practically identical with the mandrel 2 previously described. This mandrel has a member 64 for gripping the free end of the hair as before and its right hand end is mounted on a hub 65 of a disc 66. A spring clutch 67, identical with that previously described, is provided for permitting rotation of mandrel 63 in one direction relative to hub 65 but for precluding rotation thereof in an opposite direction relative to hub 65. The disc 66 is held in position at the end of the mandrel by a collar member 70, which also serves as a knob, in such a manner as to permit rotation of the mandrel relative to this disc. The outer end of mandrel 63 is provided with a knurled knob 68 by which the mandrel may be rotated in the said direction. It will be apparent that the

mandrel is thus provided with a knob 69 at one end and a knob 70 at the other end, these knobs 69 and 70 being of the same diameter, which is less than the diameter of housing 61.

The mandrel 63 is provided with a bore 71 extending entirely therethrough. The hub 65 is provided with a similar bore 72 which corresponds to bore 71 and is of the same diameter and is also provided with a bore 73 of smaller diameter which communicates therewith. A shaft 74 is mounted in a centrally disposed opening of the closed end 62 of the housing and is held non-rotatable by a pin 75 passing through an opening 76 in the end thereof and a corresponding opening 77 in the housing. When the mandrel is in the position indicated in Figure 18, the shaft 74 will extend through the bores 71, 72 and 73. The bores 71 and 72 are of substantially greater diameter than the shaft 74 in order that they may slide over a stop member 78, larger in diameter than shaft 74, formed on the outer end of the shaft. The stop 78 may be removable, if desired.

It will be apparent that reciprocation of the mandrel 63 on the shaft 74 in and out of the housing 61 will be permitted. However, complete removal of mandrel 63 will be precluded by the stop 78 as indicated in Figure 20.

The disc 66 is provided with a plurality of projections 79 on its outer surface. These projections are adapted to cooperate with corresponding sockets 80 formed in the closed end of the housing. When the mandrel 63 is in the position illustrated in Figure 18, the projections 79 will extend into the sockets 80. Thus, rotation of plate 66 relative to the housing will be precluded. When the mandrel is in its innermost position in the housing, the plate 66 will be held stationary but it will be possible to rotate the mandrel relative to this plate in one direction only. When the mandrel is in its innermost position, the knob 69 completely closes the outer end of the housing and will prevent escape of heat therefrom and of steam or fluid from the trough formed in the bottom of the housing. One side of the housing 61 is provided with a slot 81 which extends substantially the entire length thereof. This slot is disposed at that side of the housing corresponding to the side of the member 1 where the hair gripping and locking means is disposed, as indicated in Figure 21. The left hand end of this slot 81 is open and flared to permit the ready insertion of a strand of hair, as will be described later.

In using this device, the mandrel is extended from the housing 61 as far as possible. Then, the free end of a strand of hair is slipped underneath member 64 and is clamped to the mandrel. The mandrel is then rotated bodily in a counter-clockwise direction as before to wind the hair around the mandrel and member 64 spirally and in overlapping layers, as previously described. When a point close to the scalp is reached, the mandrel is moved bodily into the housing, but before this is done a pad similar to pad 42 is wrapped around the mandrel. In moving the mandrel into the housing, the lower end of the strand of hair is slipped into slot 81 and will move therethrough until the mandrel is finally positioned in the housing. Then, this lower end of the strand may be slipped into the gripping means carried by member 1 and this gripping means operated to grip the hair firmly. The next step will be to tighten or tension the hair on the mandrel. To do this, the mandrel 75

is rotated in a counter-clockwise direction by means of the knob 68 and reverse direction thereof will be precluded by the spring clutch. Tightening of the hair will also cause the mandrel to be held firmly in the housing. Since the hair will be gripped close to the scalp before the tightening operation, there will be no discomfort caused to the patron by such tightening operation.

40 Next, the heater is placed on this device. This heater may be of exactly the same structure as the heater 45 previously described. It is slipped longitudinally over the housing and will cover the slot formed in the housing. It is necessary that the ends of the inner casing of the heater be only slightly greater in diameter than the diameter of the housing, in order that the ends of the heater will be closed. Thus, escape of heat will be precluded. The knob 69 prevents escape of steam or fluid from the trough formed in the bottom of housing 61 and the closed opposite end of the housing prevents escape at that end. It will be apparent that, in this instance, also, the lower edges of the inner 25 casing of the heater extend down into trough 5 and will aid in preventing escape of heat at these points. In removing the hair, it will be necessary only to release the grip on the lower end of the strand of hair, slip the mandrel 63 out of the housing to its outermost position, and then unwind the hair therefrom.

Figure 22 shows apparatus which is similar in substantially every respect to that just described, except that the protecting member, the 30 housing for the mandrel and the heater are all made in a single unit. This unit 83 may be made of any suitable material and the upper portion forms the heating unit. The heating unit has an inner and outer casing with the space formed 35 therebetween closed at all its edges and having a heating element 84 disposed therein. The mandrel 85 is identical with that previously described and may be moved into and out of the unit 83 in the manner previously described. A slot 86 is provided in the unit 83 for the same purpose for which slot 81 of the device previously described is provided. A member 87 is provided which is adapted to receive the plug of an electrical wire adapted to supply the current to 40 the heating element. By making the heating unit and the other parts of my apparatus in a single unit in this manner, a neat appearing and easily operable structure is provided. In this instance, also, there will be no danger of 45 steam or condensed vapor reaching the scalp of 50 the patron.

It will be apparent from the preceding description that I have provided hair waving apparatus having many desirable features. With 55 my apparatus, there is no chance of steam or condensed vapor reaching the scalp of the patron and causing discomfort or injury. Another 60 advantageous feature of my invention is its simple construction. It may be made cheaply and, due to its simplicity, it can be readily applied to the hair.

Another advantage of my invention resides in the particular hair gripping means which I have provided for gripping the hair close to the scalp. 65 This gripping means is self-locking and can be readily operated. Also, this locking means is of such a type that square bunches of hair may be separated and gripped thereby, rather than rectangular bunches as used with prior art devices. This makes it possible to produce the

wave in the hair even at points close to the scalp.

Still another advantage lies in the particular type of heating unit which I have devised. This heating unit is very simple in structure and can be cheaply made. It is made in a single section and differs from prior art heaters embodying two sections hinged together and having springs for maintaining the sections in clamping relation to the mandrel. Thus, my heater is much more simple than the prior art type. It can be readily applied to the hair waving device and effectively cooperates therewith in various ways previously mentioned. Many other advantages will be readily apparent.

Having thus described my invention, what I claim is:

1. A hair waving device comprising a protecting member, a housing on said protecting member, a mandrel mounted on said protecting member, said mandrel being adjustable from a position inside of said housing longitudinally of the housing to a position outside of said housing.

2. A hair waving device comprising a mandrel, a housing for said mandrel, said housing having one end open, said mandrel being adjustable from a position within said housing longitudinally of the housing to a position where it extends from the end of said housing, said mandrel having means thereon for closing the open end of said housing.

3. Apparatus for waving hair comprising a protecting member having a trough formed in its upper surface with the bottom of said trough continuous so as to prevent escape of liquid or vapor therethrough, said protecting member having an open-ended slot formed in one edge thereof which is adapted to receive a strand of hair, a plate member adjustable back and forth across said slot to retain a strand of hair therein or to permit removal of the strand therefrom, worm and gear mechanism for adjusting said plate and locking it in position, a mandrel mounted on the upper side of said protecting member, said mandrel having one end pivoted to said protecting member and being swingable between operative and inoperative positions, said mandrel having a knob thereon which fits into said trough when the mandrel is in operative position and which will prevent passage of liquid or vapor by the knob from the trough, means in said mandrel for securing the free end of a strand of hair thereto, means for permitting rotation of said mandrel on said protecting member in one direction but for precluding rotation thereof in an opposite direction, a heating unit made up in a single unit and having a chamber for receiving said mandrel, said heating unit being slidable longitudinally over said mandrel and having portions which extend into said trough and overlap the bottom thereof, the knob on said mandrel being also provided for closing an open end of the chamber in said heater to prevent escape of heat or fluid therefrom.

4. Apparatus for waving hair comprising a protecting member having a trough formed in its upper surface with the bottom of said trough continuous so as to prevent escape of liquid or vapor therethrough, said protecting member having an open-ended slot formed therein which is adapted to receive a strand of hair, a member adjustable into a position where it will retain the hair in said slot or into a position where it will permit removal thereof, a mandrel mounted

on the upper side of said protecting member, said mandrel having one end pivoted to said protecting member and being swingable between operative and inoperative positions, said mandrel having a knob thereon which fits into said trough when the mandrel is in operative position and which will prevent passage of liquid or vapor by the knob from the trough, means in said mandrel for securing the free end of a strand of hair thereto, means for permitting rotation of said mandrel on said protecting member in one direction but for precluding rotation thereof in an opposite direction, a heating unit made up in a single unit and having a chamber for receiving said mandrel, said heating unit being slidable longitudinally over said mandrel and having portions which extend into said trough and overlap the bottom thereof, the knob on said mandrel being also provided for closing an open end of the chamber in said heater to prevent escape of heat or fluid therefrom.

5. Apparatus for waving hair comprising a protecting member having a trough formed in its upper surface with the bottom of said trough continuous so as to prevent escape of liquid or vapor therethrough, means on said protecting member for gripping a strand of hair at a point close to the scalp, a mandrel mounted on the upper side of said protecting member, said mandrel having one end pivoted to said protecting member and being swingable between operative and inoperative positions, said mandrel having a knob theron which fits into said trough when the mandrel is in operative position and which will prevent passage of liquid or vapor by the knob from the trough, means on said mandrel for securing the free end of a strand of hair thereto, means for permitting rotation of said mandrel on said protecting member in one direction but for precluding rotation thereof in an opposite direction, a heating unit made up in a single unit and having a chamber for receiving said mandrel, said heating unit being slidable longitudinally over said mandrel, a knob on said mandrel being also for closing an open end of the chamber in said heater to prevent escape of heat or fluid therefrom.

30 6. Apparatus for waving hair comprising a protecting member having a trough formed in its upper surface with the bottom of said trough continuous so as to prevent escape of liquid or vapor therethrough, said protecting member having an open-ended slot formed in one edge thereof which is adapted to receive a strand of hair, a plate member adjustable back and forth across said slot to retain a strand of hair thereon or to permit removal of the strand therefrom, worm and gear mechanism for adjusting said plate and locking it in position, a mandrel mounted on the upper side of said protecting member, said mandrel being fastened to said protecting member but being adjustable between operative and inoperative positions, said mandrel having a knob thereon which fits into said trough when the mandrel is in operative position and which will prevent passage of liquid or vapor by the knob from the trough, means on said mandrel for securing the free end of a strand of hair thereto, means for permitting rotation of said mandrel on said protecting member in one direction but for precluding rotation thereof in an opposite direction, a heat-

ing unit made up in a single unit and having a chamber for receiving said mandrel, said heating unit being slidable longitudinally over said mandrel, the knob on said mandrel being also provided for closing an open end of the chamber in said heater to prevent escape of heat or fluid therefrom.

7. Apparatus for waving hair comprising a protective member having a trough formed in its upper surface with the bottom of said trough continuous so as to prevent escape of liquid or vapor therethrough, means on said protecting member for gripping a strand of hair at a point close to the scalp, a mandrel mounted on the upper side of said protecting member, said mandrel being fastened to said protecting member but being adjustable between operative and inoperative positions, said mandrel having a knob thereon which fits into said trough when the mandrel is in operative position and which will prevent passage of liquid or vapor by the knob from the trough, means on said mandrel for securing the free end of a strand of hair thereto, means for permitting rotation of said mandrel on said protecting member in one direction but for precluding rotation thereof in an opposite direction, a heating unit made up in a single unit and having a chamber for receiving said mandrel, said heating unit being slidable longitudinally over said mandrel, a knob on said mandrel being also for closing an open end of the chamber in said heater to prevent escape of heat or fluid therefrom.

25 8. Apparatus for waving hair comprising a protecting member having a trough formed in its upper surface with the bottom of said trough continuous so as to prevent escape of liquid or vapor therethrough, means on said protecting member for gripping a strand of hair at a point close to the scalp, a mandrel mounted on said protecting member, said mandrel being fastened to said protecting member but being adjustable longitudinally thereof into and out of said trough, said mandrel having a knob thereon which fits into said trough when the mandrel is disposed therein and which will prevent passage of fluid by the knob from the trough, means on said mandrel for securing the free end of a strand of hair thereto, means for permitting rotation of said mandrel on said protecting member in one direction but for precluding rotation thereof in an opposite direction, a heating unit made up in a single unit and having a chamber for receiving said mandrel, said heating unit being slidable longitudinally over said mandrel, a knob on said mandrel being also for closing an open end of the chamber in said heater to prevent escape of heat or fluid therefrom.

30 9. Apparatus for waving hair comprising a protecting member having a trough formed in its upper surface with the bottom of said trough continuous so as to prevent escape of liquid or vapor therethrough, said protecting member having an open-ended slot formed in one edge thereof which is adapted to receive a strand of hair, a plate member adjustable back and forth across said slot to retain a strand of hair thereon or to permit removal of the strand therefrom, worm and gear mechanism for adjusting said plate and locking it in position, a mandrel mounted on the upper side of said protecting member, said mandrel having one end pivoted to said protecting member and being swingable between operative and inoperative positions, said mandrel having a knob thereon which fits into said trough when the mandrel is in operative position.

- position and which will prevent passage of liquid or vapor by the knob from the trough, means on said mandrel for securing the free end of a strand of hair thereto and means for permitting 5 rotation of said mandrel on said protecting member in one direction but for precluding rotation thereof in an opposite direction.
10. Apparatus for waving hair comprising a protecting member having a trough formed in its upper surface with the bottom of said trough continuous so as to prevent escape of liquid or vapor therethrough, said protecting member having an open-ended slot formed thereon which is adapted to receive a strand of hair, a member 15 adjustable into a position where it will retain the hair in said slot or into a position where it will permit removal thereof, a mandrel mounted on the upper side of said protecting member, said mandrel having one end pivoted to said protecting member and being swingable between operative and inoperative positions, said mandrel having a knob thereon which fits into said trough when the mandrel is in operative position and which will prevent 20 passage of liquid or vapor by the knob from the trough, means on said mandrel for securing the free end of a strand of hair thereto and means for permitting rotation of said mandrel on said protecting member in one direction but for precluding rotation thereof in an opposite direction. 25
11. Apparatus for waving hair comprising a protecting member having a trough formed in its upper surface with the bottom of said trough continuous so as to prevent escape of liquid or vapor therethrough, means on said protecting member for gripping a strand of hair at a point close to the scalp, a mandrel mounted on the upper side of said protecting member, said mandrel having one end pivoted to said protecting member and being swingable between operative and inoperative positions, said mandrel having a knob thereon which fits into said trough when the mandrel is in operative position and which will prevent passage of liquid or vapor by the knob from the trough, means on 30 said mandrel for securing the free end of a strand of hair thereto and means for permitting rotation of said mandrel on said protecting member in one direction but for precluding rotation thereof in an opposite direction. 35
12. Apparatus for waving hair comprising a protecting member having a trough formed in its upper surface with the bottom of said trough continuous so as to prevent escape of liquid or vapor therethrough, means on said protecting member for gripping a strand of hair at a point close to the scalp, a mandrel mounted on said protecting member, said mandrel being fastened to said protecting member but being adjustable longitudinally thereof into and out of said trough, said mandrel having a knob thereon which fits into said trough when the mandrel is disposed therein and which will prevent passage of fluid by the knob from the trough, means on said mandrel for securing the free end of a strand of hair thereto and means for permitting 10 rotation of said mandrel on said protecting member in one direction but for precluding rotation thereof in an opposite direction. 15
13. In apparatus for waving hair, a protecting member having a trough formed in its upper surface with the bottom of said trough continuous so as to prevent escape of liquid or vapor therethrough, said protecting member having an open-ended slot formed in one edge thereof which is adapted to receive a strand of hair, a 20 plate member adjustable back and forth across said slot to retain a strand of hair therein, or to permit removal of the strand therefrom and worm and gear mechanism for adjusting said plate and for locking it in position. 25
14. In apparatus for waving hair, a protecting member having a trough formed in its upper surface with the bottom of said trough continuous so as to prevent escape of liquid or vapor therethrough, said protecting member having an open-ended slot formed in one edge thereof which is adapted to receive a strand of hair and a member adjustable into a position where it will retain the hair in said slot or into a position where it will permit removal thereof. 30 35 40 45

PETER SANTURELLO.
